ICE TRAY GRID

Clifford R. Carney, Dearborn, Mich.

Application June 24, 1940, Serial No. 342,008

12 Claims. (Cl. 62—108.5)

The present invention relates to an ice tray grid construction for use in a refrigerator ice tray. The grid construction of the present invention is intended to be used with trays or pans in domestic refrigerators to provide a desired quantity of frozen ice cubes which may be easily removed from the tray.

The objects of the present invention are:

First, to provide an ice tray grid which upon actuation will readily release ice cubes frozen between the various compartments of the grid member, the said grid being of a simplified construction and readily adapted for large scale manufacture on a production basis.

Second, to provide an ice tray grid of simplified construction which is economical to manufacture, efficient in its operation, and which is rugged and durable in its construction.

Third, to provide an ice tray grid constructed of a plurality of rigid members which are connected together to provide for limited movement of all members of the grid relative to each other for the purpose of breaking the frozen bond between the surfaces of the ice cubes and the adjacent surfaces of the grid members and the pan and in which the actuating lever and force applying members are an integral part of the grid structure.

Other objects and advantages of this invention will appear in the following description and appended claims, reference being had to the accompanying drawing forming a part of this specification wherein like reference characters designate corresponding parts in the several views.

In the drawing:

Fig. 1 is a view in perspective of an ice tray having placed therein a grid embodying the present invention. This view shows the respective parts of the grid in the positions which they occupy when the tray and grid are frozen with ice cubes therein or just prior to the freezing of water contained therein.

Fig. 2 is a sectional view taken substantially on the line 2—2 of Fig. 1 looking in the direction of the arrows.

Fig. 3 is a longitudinal section taken substantially on the line 3—3 of Fig. 2 looking in the direction of the arrows.

Fig. 4 is a fragmentary top plan view showing the operating lever and connected parts of the grid shown in Figs. 1 to 3 inclusive.

Fig. 5 is a view similar to Fig. 3 but showing the relative position of the parts of the grid upon the completion of movement intended to break the

bond between ice cubes, the tray, and the adjacent parts of the grid mechanism.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings and particularly to Fig. 1, the ice tray and grid of the present invention is shown in a refrigerator pan or tray 10 which may be of any desired conventional construction. The grid structure to which the present invention particularly relates comprises a plurality of longitudinal members 11 which in the present instance are three in number. It is to be understood, however, that any desired number of such members may be employed so long as the number is three or more. The longitudinal members 11 are provided with inclined end portions 12 which extend to points adjacent to the ends of the ice tray 10 and divide the tray 10 into a plurality of compartments which extend longitudinally of the said tray. In the present instance where three of the longitudinal members 11 extend longitudinally of the tray 10 these longitudinal compartments are four in number.

Secured to each of the longitudinal members 11 and spaced throughout the length of the tray 10 are a plurality of transverse members 13 which extend across the width of the pan 10 and serve to divide the pan 10 into a plurality of longitudinally spaced transverse chambers. In the present preferred embodiment of the invention, four of the members 13 are provided in the grid and divide the tray 10 into five transverse chambers. Thus, the grid construction of the present invention, when utilizing three longitudinal members 11 and four transverse members 13, provides for dividing the contents of the pan 10 into twenty separate cubes.

The longitudinal members 11 and the transverse members 13 are connected to permit relative movement of the longitudinal members relative to the transverse members 13 and relative to each other and likewise to provide for relative movement of the transverse members 13 relative to the longitudinal members 11 and relative to the other of the transverse members 13. One form of suitable connection between the transverse

members 13 and the longitudinal members 11 is shown in Figs. 2 and 3. As here shown, a plurality of pierced slots 14 is provided in each of the longitudinal members 11. The slots 14 in the central longitudinal member are preferably larger than the slots 14 in the other longitudinal members. Each of the longitudinal members 11 is also provided with a plurality of cut-away portions 15. In the embodiment here shown the cut-away portions 15 are provided adjacent the top longitudinal edge of each of the longitudinal members 11 and the pierced openings 14 are provided adjacent the lower edge of each of the members 11 but are spaced slightly therefrom so that the lower edge of each of the members 11 forms a continuous unbroken line which contacts the bottom of the pan or tray 10 throughout its length. As shown in Fig. 2, each of the transverse members 13 is provided with inclined slotted portions 16 and 17 and a substantially vertically extending centrally located slot 18. The slots 16, 17 and 18 are so shaped and arranged that the centrally disposed longitudinal member 11 will be held in the central seat 18 in a substantially vertical position relative to the pan 10 and the side longitudinal members 11 will be held in the slots 16 and 17 and in a position inclined slightly from the vertical, preferably in such a direction that the top surfaces of each of the side longitudinal members 11 will incline toward the centrally placed longitudinal member 11.

The transverse members 13 are each provided with lugs 19 which are pressed through the openings 14 provided in the longitudinal members 11. The lugs 18 and 19 when pressed through the openings 14 in each of the members 11, serve to lock the longitudinal members 11 and the transverse members 13 in their assembled positions, while permitting a free relative movement of the transverse members 13 relative to the longitudinal members 11.

At the same time the slots 15 in the top edges of the longitudinal members 11 permit the transverse members 13 to occupy an angularly inclined position, as for example shown in Fig. 3. This construction, it will be noted, also permits relative movement of the longitudinal members 11 relative to each other as well as to the transverse members 13 and also permits independent movement of the transverse members 13 relative to each other as well as relative to the longitudinal members 11.

Before describing the operation of a grid embodying the present invention, it will be assumed that a tray 10 is provided with a grid consisting of the longitudinal members 11 and the transverse members 13 which occupy the positions shown in Fig. 1, and that water has been placed therein and frozen to form ice cubes in the compartments defined by the adjacent walls of the pan 10, the longitudinal members 11 and the transverse members 13. When frozen in this position, relative movement of the longitudinal members 11 relative to each other and of the transverse members 13 relative to each other, and the movement of the longitudinal members 11 and the transverse members 13 relative to each other, breaks the surface adhesion between the ice cubes and the adjacent walls of the pan 10, the longitudinal members 11 and the transverse members 13 and permits ready removal of the said cubes from the grid and the pan. This relative movement of the parts of the grid is accomplished by actuation of the operating handle 20 which is connected to an operating cam shaft

21 which is pivotally mounted in such a manner that each of the ends thereof is mounted for rotation in journal openings provided in the side longitudinally extending members 11. The journal openings provided in the side longitudinal members 11 are aligned in a transverse direction when the tray and grid occupies the relative position shown in Fig. 1. The central longitudinal member 11 is provided with a U-shaped slot 22 which is adapted to receive and be contacted by a central portion 23 of the cam shaft 21. As here shown the slot 22 is provided at a point which is normally in advance of the transverse line on which the cam shaft 21 is journaled in the side longitudinally extending members 11. The raising of the handle 20 in the direction indicated by the arrow, Fig. 5, thus causes rotation of the cam shaft 21 in the journals provided in the side longitudinal members 11. The 10 points of pivotal connection between the cam shaft 21 and the side longitudinal members 11 act as a fulcrum about which the handle 20 moves as the actuating arm of the lever system is thus set in motion. This pivotal movement 20 of the handle 20 causes a force to be exerted by the cam portion 23 of the cam shaft 21 in the slot 22 provided in the central longitudinally extending member 11 and this force causes movement of said central longitudinal member 11 relative to said side longitudinal members 11 and in a direction extending longitudinally of the tray 10. As the handle 20 is moved from the folded position of Fig. 1 to the elevated position of Fig. 5 the cam portion 23 also exerts a force in downward direction on the slot 22 provided in the central longitudinal member 11. As this force is exerted through the cam 23 to the central longitudinal member 11, the cam shaft 21 transmits the force to the connected side longitudinal members 11 and causes a movement of said members in a generally vertical direction which causes them to be elevated to the position shown in Fig. 5 where one end of each of the side members 11 is moved angularly in an upward direction 45 relative to the bottom of tray 10.

The above described movement of the central longitudinal member 11 is thereafter transmitted to each of the transverse members 13 and causes each of the members 13 to be moved from its angularly inclined position, shown in Fig. 3, to a relatively more vertical position shown in Fig. 5.

It is to be understood in connection with the operation of devices of this type that a very slight movement is all that is required to break 55 the adhesion between surfaces of the ice cubes and the adjacent surfaces of the tray 10, the longitudinal grids 11 and the transverse grids 13. This amount of movement is provided in the present structure by spacing the ends of the 60 longitudinal members 11 a slight distance from the inner surfaces of the ends of the pan 10. This permits the relative movement of the central longitudinal member 11 which has previously been discussed.

As the handle 20 is actuated and the central longitudinal member 11 is moved lengthwise of the grid relative to the other longitudinal members, the lugs 19 of the transverse members 13 move in the enlarged slots 14 in the central longitudinal member 11. The edges 30 defining the slots 15 in the central longitudinal member 11 engage the adjacent faces of the transverse members 13 and move them longitudinally in the direction of movement of the central member. 75 The slots 14 formed in the outside longitudinal

members 11 which are moved in the opposite direction to movement of the central member 11 prevent the transverse members 13 from moving longitudinally relative to the grid. The transverse members 13 are therefore moved angularly from their normal angularly inclined or ice forming positions towards the vertical position to release ice.

Upon movement of the transverse members 13 toward the positions occupied in Fig. 5, there is a pivotal movement of each transverse member 13 about the lugs 19 in the openings 14 provided in the longitudinal members 11. As this pivotal movement continues a camming action is exerted by the slots 16 and 17 on the longitudinal members 11 which extend therethrough since the upper edges of the front inclined transverse members 13 are moved in an arc, the center of which is the point of pivotal connection between the lower edges of the transverse members 13 and the longitudinal members 11. Due to this arcuate movement of the top surfaces of the transverse members 13, the upper edges of the side longitudinal members 11 are moved outwardly relative to the central longitudinal member 11 and are caused to assume a more nearly vertical position than that shown in Fig. 2. This effects a further breaking or shearing action between the adjacent surfaces of the longitudinal members 11 and the ice cubes frozen therein.

As the handle 20 is moved to its fully raised position, as shown in Fig. 5, a force is exerted through the longitudinal members 11 on one end of the pan 10 and this together with the elevation of the opposite ends of the side longitudinal members previously described elevates the entire grid structure angularly relative to the pan 10 and completes the ice freeing action.

From the foregoing it will be seen that I have provided a novel ice tray grid structure in which relative movement of the structural members forming the grid is initiated and controlled by actuation of the handle 20. Due to the multiplication of forces applied to the handle 20, through the cam 23 and the integral parts of the grid structure operating as a lever system, a relatively small force on the handle 20 is all that is required to actuate the grid members as above described to effect the release of ice cubes therefrom. As previously described, it will be seen that pivotal movement of the handle 20 causes relative movement between the longitudinal members 11 and between the longitudinal members 11 and the transverse members 13. It will also be seen that each of the transverse members 13 is moved relative to each other and relative to the longitudinal members 11 and that the entire grid structure is moved as a unit relative to the tray 10. Thus it will be seen that all of the connected parts of the grid member are moved according to a predetermined sequence of motion when the said handle 20 is actuated to move the members and break the ice cubes therefrom. It will also be seen that the grid structure of the present invention is positive in its operation and is at the same time of a simplified construction which readily lends itself to a large scale production on a commercial basis.

The structural members forming the grid of the present invention may be formed of any suitable material; preferably however the grid members are formed of a thermally conductive metal, such for example as aluminum or an aluminum alloy. If the metal is of a corrodible nature, it should be suitably treated to prevent

corrosion when in contact with water. The pan or tray 10 is likewise preferably formed of a thermally conductive metal or metallic alloy which if of a corrodible character is suitably treated to prevent corrosion when brought in contact with water. If the material used in the construction of the pan and grid is of aluminum or an aluminum alloy, it is preferably treated to form a hard surface coating consisting chiefly of aluminum oxide. This surface thereafter is impregnated with a suitable high melting wax, such for example as carnauba wax. By the provision of the oxide coating on the aluminum or the aluminum alloy and the impregnation of this coating with the high melting wax, the force required for the breaking of the grid structure from the ice cubes is greatly diminished since the adhesion of the surfaces of the ice cubes to surfaces of the pan and grid so treated is less than the adhesion of such cubes to surfaces which have not been so treated.

I claim:

1. An ice tray grid comprising a plurality of longitudinal separator members and a plurality of transverse members hingedly connected to the longitudinal members to provide a unitary structure in which a plurality of said longitudinal separator members are movable in opposite directions relative to each other and to said transverse members, and said transverse members are movable relative to said longitudinal separator members and relative to each other, and motion transmitting means including a pivotal connection with a plurality of longitudinal members and a cam connection with another longitudinal separator member for effecting relative longitudinal movement of said members to break adhesion between the adjacent surfaces of said grid and ice cubes frozen therein.

2. An ice tray grid comprising a plurality of longitudinal separator members and a plurality of transverse members hingedly connected to provide a unitary structure in which the longitudinal members are movable relative to each other and to said transverse members and said transverse members are movable relative to said longitudinal members and relative to each other, and means for effecting the relative movement of said members to break adhesion between the adjacent surfaces of said grid and ice cubes frozen therein, and including a handle having aligned pivotal connections with at least two longitudinal separator members and a cam movable in a slot provided in a third longitudinal separator member, said slot being out of alignment with said aligned pivotal connections whereby said third longitudinal separator member is moved relative to said two longitudinal separator members and said movement is transmitted to said plurality of transverse members.

3. An ice tray grid comprising a plurality of longitudinal members and a plurality of transverse members hingedly connected to the longitudinal members to provide a unitary structure in which one of the longitudinal members is movable longitudinally relative to a plurality of said longitudinal members and to said transverse members and said transverse members are movable relative to said longitudinal members and relative to each other, and means including a handle having aligned pivots in a plurality of longitudinal members and a cam movably mounted in a slot formed in another longitudinal member to apply forces thereto sufficient to effect movement of all of said members and break ad-

hesion between the adjacent surfaces of said grid and ice cubes frozen therein, said grid comprising three or more longitudinal members, one of which is connected with each of said transverse members and maintained in a substantially vertical plane and the others of which are connected with each of said transverse members and maintained in planes inclined from the vertical.

4. An ice tray grid comprising a plurality of longitudinal members and a plurality of transverse members hingedly connected to provide a unitary structure in which the longitudinal members are movable relative to each other and to said transverse members and said transverse members are movable relative to said longitudinal members and relative to each other, and means for effecting the relative movement of said members comprising a handle having aligned pivots in a plurality of longitudinal members and a cam movably mounted in a slot formed in another longitudinal member to break adhesion between the adjacent surfaces of said grid and ice cubes frozen therein, said grid comprising three or more longitudinal members, one of which is movable longitudinally relative to two or more longitudinal members and is connected with each of said transverse members and maintained in a substantially vertical plane and two of which are connected with each of said transverse members and maintained in planes inclined from the vertical, the lower edges of said longitudinal members being spaced transversely of the pan a greater distance than are the upper edges thereof.

5. An ice tray grid comprising a plurality of longitudinal members and transverse members connected to provide a unitary structure in which all of said members are movable relative to each other and to the other of said members, and means for effecting movement of said connected members and including a handle pivotally connected with a plurality of said longitudinal members and adapted when raised to move said plurality of longitudinal members vertically and longitudinally relative to another longitudinal member and relative to said transverse members, said longitudinal movement effecting movement of said transverse members relative to each other and relative to said longitudinal members to break the adhesion between the surfaces of said members and ice cubes frozen thereto.

6. An ice tray grid comprising a plurality of longitudinal members and transverse members connected to provide a unitary structure in which all of said members are movable relative to each other and to the other of said members, and means for effecting movement of said connected members and including a handle pivotally connected with a plurality of said longitudinal members and adapted when raised to move another of said longitudinal members relative to said plurality of longitudinal members and relative to said transverse members, said movement effecting movement of said transverse members relative to each other and relative to said longitudinal members to break the adhesion between the surfaces of said members and ice cubes frozen thereto, said transverse members having slots therein adapted to permit the extension of said longitudinal members therethrough and having hinge connections with said longitudinal members adjacent the bottom edges thereof.

7. An ice tray grid comprising a plurality of longitudinal members and transverse members connected to provide a unitary structure in which all of said members are movable relative to each

other and to the other of said members, and means for effecting movement of said connected members and including a handle pivotally connected with said longitudinal members and adapted when raised to move said longitudinal members longitudinally relative to each other and relative to said transverse members, said movement effecting movement of said transverse members relative to each other and relative to said longitudinal members to break the adhesion between the surfaces of said members and ice cubes frozen thereto, said transverse members having slots therein adapted to permit the extension of said longitudinal members therethrough and having hinge connections with said longitudinal members adjacent the bottom edges thereof; said slots including a central slot extending in a substantially vertical plane and slots disposed on each side of said central slot and angularly inclined from the vertical.

8. An ice tray grid comprising a plurality of longitudinal members and transverse members connected to provide a unitary structure in which all of said members are movable relative to each other and to the other of said members, and means for effecting movement of said connected members and including a handle pivotally connected with said longitudinal members and adapted when raised to move said longitudinal members vertically relative to each other and relative to said transverse members, said movement effecting movement of said transverse members relative to each other and relative to said longitudinal members to break the adhesion between the surfaces of said members and ice cubes frozen thereto, said transverse members having a series of slots therein adapted to permit the extension of said longitudinal members therethrough and providing a support for maintaining said longitudinal members in predetermined positions, said transverse members each having a hinge connection with each of said longitudinal members at points adjacent the bottom edges thereof, said slots including a central slot extending in a substantially vertical plane and a slot disposed on each side of said central slot and inclined angularly from the vertical, the lower ends of said side slots being spaced a greater distance from the central slot than are the upper ends of said side slots.

9. An ice tray grid comprising a plurality of longitudinal separator members and transverse members connected to provide a unitary structure in which all of said transverse members are movable relative to each other and relative to said longitudinal members to break the adhesion between the surfaces of said members and ice cubes frozen thereto, means for effecting relative movement of said members including a handle having aligned pivotal connections with at least two longitudinal separator members and a movable connection with a central longitudinal separator member, the connection with the central longitudinal member being out of alignment with the pivotal connections between said two longitudinal members at said handle whereby movement of said handle effects a movement of said central member relative to said two longitudinal members.

10. An ice tray grid comprising a central and a pair of side longitudinal separator members and a plurality of transverse members hingedly connected thereto, and a handle pivotally connected with said side longitudinal separator members and having a cam connection with said
